DESIGN FOR A CHEESE KNIFE

John Fiedler, Dayton, Ohio

Application October 31, 1947, Serial No. 142,244

Term of patent 7 years

(Cl. D22—3)

To all whom it may concern:

Be it known that I, John Fiedler, a citizen of the United States, residing in Dayton, in the county of Montgomery, State of Ohio, have invented a new, original, and ornamental Design for a Cheese Knife, of which the following is a specification, reference being had to the accompanying drawing, forming a part thereof.

Fig. 1 is a front elevation of a cheese knife showing my new design; Fig. 2 is a top plan view of said cheese knife; and Fig. 3 is an enlarged end elevation thereof.

I claim:

The ornamental design for a cheese knife, as shown.

JOHN FIEDLER.
